ROTARY KILN

Charles S. Glenn, Syracuse, N. Y., assignor to The
Mathieson Alkali Works, Inc., New York, N. Y.,
a corporation of Virginia

Application May 27, 1935, Serial No. 23,657

1 Claim. (Cl. 263—33)

This invention relates to improvements in rotary kilns with countercurrent firing. The accompanying drawings illustrate a rotary kiln embodying the invention. With the exception of 5 the parts numbered 12, 13 and 14, the rotary kiln illustrated is of conventional construction.

In the conventional rotary kiln with countercurrent firing, as arranged for the calcination of limestone or other calcareous carbonate to produce lime for example, the kiln proper is inclined 10 so that rotation of the kiln carries the solids moving through the kiln to the lower end from which they are discharged and at which end the kiln is fired. In the usual conventional construction, 15 the lower end of the kiln proper extends into a firing hood within which a bridge wall is arranged transversely of the axis of rotation of the kiln proper, solids being discharged on the side of the bridge wall facing the kiln proper and combustion air being supplied to the firing hood on 20 the other side of the bridge wall. In the rotary kiln illustrated in the accompanying drawings, the lower end of the kiln is designated 5, the firing hood is designated 6, the bridge wall is designated 7, the discharge chute for solids is 25 designated 8 and the duct for supplying combustion air is designated 9. In this conventional construction, dust or fines tend to accumulate in the space within the firing hood on the hood side of the 30 bridge wall. Such accumulations have been limited to prevent direct interference with the kiln operation by pushing accumulating dust or fines over the bridge wall or by pulling it out through ports in the hood by means of slicing bars and rabbles manually worked through ports in the 35 hood. The extra labor, the dilution of the kiln gases with atmospheric nitrogen, the admission of cool and usually excess air, and the contamination of the atmosphere adjacent the firing end 40 of the kiln involved in this procedure have been regarded as necessary evils. Such accumulations of dust or fines, easily suspended in the gases moving through the kiln, further, provide a supply of such dust or fines in a region such that it 45 tends to build up an increasing concentration of such dust or fines in the combustion zone, the dust or fines moving in a cycle of progressively increasing concentration from the kiln proper into the firing hood and back into the kiln proper 50 and so on. This concentration of dust or fines in the gases of combustion within the firing hood and at the firing end of the kiln proper frequently reaches a point interfering with the efficiency 55 of the kiln operation and the regularity of the kiln operation.

I have found that important improvements in efficiency of operation and regularity of operation of rotary kilns of this construction are to be attained by providing means facilitating the discharge of dust or fines from the space on the 5 hood side of the bridge wall so that accumulations of dust or fines in this region can be limited not only to an extent sufficient to eliminate the manual operations previously mentioned but also to prevent such accumulations as tend to 10 produce those concentrations of suspended dust or fines in the combustion gases in the firing hood and in the firing end of the kiln proper interfering with the efficiency and regularity of the 15 operation. A particularly advantageous embodiment of such means is illustrated in the accompanying drawings in which Fig. 1 is a fragmentary vertical section transverse to the axis of rotation of the kiln proper through the firing hood between the bridge wall and the lower end of the 20 kiln proper of a kiln embodying my invention, Fig. 2 is a fragmentary vertical section parallel to that illustrated in Fig. 1 through the firing hood on the other side of the bridge wall, Fig. 3 is a fragmentary vertical section of the firing 25 hood and lower end of the kiln proper through the axis of rotation of the kiln proper and Fig. 4 is a fragmentary elevation parallel to the section illustrated in Fig. 3.

In the rotary kiln illustrated in the accompanying drawings, the lower end 5 of the kiln proper extends into the firing hood 6 through a conventional seal 10. A bridge wall 7 is arranged transversely of the axis of rotation of the kiln proper across the interior of the firing hood 30 and spaced from the lower end of the kiln proper. A burner for whatever fuel or combination of fuels is used in firing the kiln opens into the firing hood 6 through port 11. Solids moving out of the lower end of the kiln proper drop into the space between the lower end of the kiln proper and the bridge wall 7 and are discharged through chute 8. Combustion air, or other combustion supporting gas, enters the firing hood through duct 9 opening into the space on the hood side of the bridge wall 7. The kiln structure so far described in this paragraph is a conventional construction. Referring particularly to Fig. 2, in such conventional construction, however, a solid floor extends across the space constituting the opening into the hopper 12 and it is particularly in the space above such floor and between the bridge wall and the end of the hood that dust or fines accumulate in conventional construction 40 of this type.

In accordance with this invention, however, I provide a hopper 12 beneath and opening into the space on the hood side of the bridge wall 7 so proportioned that a minimum of horizontal surfaces upon which dust or fines might tend to accumulate is left within this region in the firing hood and, in conjunction with this hopper, I provide appropriate discharge means 13 to permit discharge of dust or fines collecting in the hopper either continuously or at intervals such that any tendency toward increase in concentration of dust or fines suspended in the combustion gases in the firing hood and in the lower end of the kiln proper is avoided. In the particular construction illustrated in the accompanying drawings, the lower end of the discharge means 13 is closed by a manually operated slide gate 14. The rate of collection of dust or fines in the hopper 12 in particular instances will determine the nature of the means appropriate for discharge of dust or fines from this hopper.

The chute 8 and the duct 9 may communicate, for example, with any suitable means for preheating the combustion air by heat exchange with the hot solids discharged from the rotary kiln. This invention is of special value and application in connection with installations including heat exchange means for this purpose the operation of which tends to resuspend in the combustion air passing to the firing hood dust or fines leaving the

kiln as part of the solids discharged therefrom, through chute 8 for example. In such installations, any such tendency increases the rate at which dust or fines would otherwise tend to accumulate within the firing hood. The more effective direct heat exchangers used for this purpose are usually subject to this tendency to a large extent.

This invention provides for the elimination of such accumulations within the firing hood from sources within or without the kiln and thus assists in eliminating a disadvantage to which such more effective heat exchangers might otherwise be subject.

I claim:

In rotary kilns with countercurrent firing in which the lower end of the kiln proper extends into a firing hood within which a bridge wall is arranged transversely of the axis of rotation of the kiln proper dividing the lower part of the hood into a space through which solids are discharged and a space through which combustion air enters, the improvement which comprises a hopper beneath and opening into the space through which combustion air enters including means for discharging dust or fines collecting therein so proportioned as to minimize horizontal surfaces in the space on the hood side of the bridge wall.

CHARLES S. GLENN. 30
